BUILT-UP BOBBIN

Lavern J. Jordan, Fairview Village, Ohio, assignor
to Industrial Rayon Corporation, Cleveland,
Ohio, a corporation of Delaware

Application January 30, 1939, Serial No. 252,007

3 Claims. (Cl. 242—118)

The present invention provides a built-up bobbin which can be manufactured at very low cost, which is extremely rigid, and which, while light in weight, is very durable. Among other things, 5 the invention provides a bobbin of this type which may be handled without damaging the material wound thereon. The parts of the bobbin which come into contact with the thread are preferably of non-metallic material such as hard rubber, 10 Bakelite, or other synthetic resin, while the parts which serve to hold the bobbin together are preferably of metal. The latter parts are so arranged as to provide one or more bearing surfaces within the bobbin.

15 For convenience, but in no sense of limitation, the invention will be described as applied to a bobbin particularly adapted for use in cap-twisting apparatus.

In the accompanying drawing, in which like 20 reference characters refer to like parts throughout, Figure 1 is a side elevation, partly in section, of cap-twisting apparatus in which is employed a bobbin embodying the features of the instant invention. Figure 2 represents, on an enlarged 25 scale, a side elevation of the bobbin as seen from line 2—2 of Figures 3 and 4. Figure 3 is a plan of the bobbin. Figure 4 is a bottom view of the bobbin. Figure 5 is a sectional elevation of the bobbin as seen from lines 5—5 of Figures 3 and 4.

30 In Figure 1, a portion of the cap-twisting apparatus is shown in side elevation, but it will be understood that a number of similar cap-twisting units are disposed side by side along the operating face of the apparatus. In each of 35 said units, thread 1, supplied from a suitable source, passes through guide 2 to bobbin 3, employed in and in effect forming part of the cap-twister indicated generally at 4. The guide 2 is mounted on shield 5, one of which is disposed between 40 each pair of adjacent cap-twisting units to prevent entangling of adjacent "balloons" formed by thread 1. As many as fifty, or even more, such threads may proceed to their respective bobbins and be twisted simultaneously on 45 one side of the same machine.

The illustrated cap-twisting apparatus operates in the usual manner, that is, the bobbin 3, while being rotated, is reciprocated into and out of the cap 6, such bobbin 3 being shown in its lowermost 50 position in Figure 1.

In operation, the bottom edge of cap 6 serves to guide thread 1 as it is wound on bobbin 3. The cap 6 for each cap-twisting unit is mounted in a stationary position at the upper end of a 55 spindle 7 which extends axially through the bob-

bin 3 and the bobbin-supporting whorl 8. Spindle 7 is non-rotatably mounted on fixed rail 9 which extends lengthwise of the machine as a whole supporting the spindles for a plurality of adjacent cap-twisters. Fixed rail 9 is rigidly attached to member 11 which forms part of the frame of the machine.

Bobbin-supporting whorl 8 for each cap-twister is mounted for rotation on vertically reciprocable lifter rail 12 which, like fixed rail 9, 10 extends lengthwise of the machine as a whole. Members 13, of which at least two are provided, are fixed to lifter rail 12, as well as to rail 14 upon which is mounted belt guide pulley 15. Each of members 13 is slidably disposed on a guide rod 16 15 rigidly mounted on frame 11 by means of fixed rail 9 and bracket 17. Whorl 8 is rotated at a high speed by belt 18 driven by suitable means (not shown). Bobbin 3 is mounted on whorl 8, driving engagement therebetween being secured 20 by suitable means as by pins on whorl 8 which project into recesses in the base of bobbin 3.

Vertical reciprocation of bobbin 3 is effected by lever arm 19 actuated by a suitable cam mechanism. A chain 21 is connected at its one 25 end to the end of lever arm 19 and at its other end to a sprocket on shaft 22, which is rotatably mounted on the frame of the machine by means of spaced brackets 23. Up-and-down movement of the end of lever arm 19 therefore causes the 30 shaft 22 to rotate about its axis, first in one direction and then in the other. Chains 24 connected to members 13 and sprockets 25 fixed to and spaced lengthwise of the shaft 22 cause the lifting rail 12 and associated mechanism to reciprocate 35 vertically.

Bobbin 3, shown in detail in Figures 2 to 5, inclusive, comprises a central tube 27, a hollow cylindrical body portion 28 surrounding said tube 27, and heads 29 and 30 at each end of said body 40 portion. The tube 27, which serves to clamp the assembly together, is of metal, preferably steel. The metal of which tube 27 is constructed should be sufficiently malleable to permit the ends thereof to be flanged over heads 29 and 30, as 45 shown in Figures 3, 4 and 5, but not so malleable as to permit the flanged portions of the tube to have an undue amount of flexibility.

It is desirable that, as shown, the tube 27 be of reduced diameter at its ends, so that the portions 50 32 and 33 of the tube may constitute bearing surfaces. For this purpose, the diameter of the tube may be reduced at its ends from an original diameter equal to that of the intermediate portion; alternatively, the intermediate portion of 55

the tube may be expanded from an original diameter equal to that of the ends. In any event, it is desirable that portions 32 and 33 be machined to accurate internal size to fit the bolster of the cap-twisting apparatus. As shown in Figure 5, the length of portion 32 of tube 27 is preferably greater than that of portion 33.

A hollow cylindrical body portion 28, constituting the barrel of the bobbin, surrounds tube 27, 10 but, as shown in Figure 5, is considerably shorter than said tube.

Upper head 29 fits over the upper end of cylindrical body portion 28, being provided with a recess 34 in which the upper end of body portion 15 28 fits closely. Lower head 30 is provided with a similar recess 35 in which is received the lower end of body portion 28. A lug 36 is formed in the circular recess of each head, said lug fitting in a notch 37 in the end of cylindrical body portion 28. 20 Lugs 36 and notches 37 cooperate to prevent relative rotation between body portion 28 and heads 29 and 30.

Upper head 29 is provided with a central bore 38 of such dimensions as to provide a snug fit for 25 the end portion 32 of tube 27, while lower head 30 is provided with a central bore 39 closely fitting the end portion 33 of tube 27. Each of said heads is preferably provided on its outer face with a recess 41 which may as shown be comparatively 30 shallow but is of larger diameter than the central bore in said head. The flanges 42 at the ends of the tube 27, by means of which the tube 27 clamps the heads 29 and 30 against body portion 28, are disposed in said recesses 41, as a 35 result of which the ends of the tube 27 do not extend beyond the faces of the heads 29 and 30. The bottom of each of the recesses 41 is preferably tapered as shown in Figure 5 to aid in clamping the heads 29 and 30 together.

40 Upper head 29 preferably includes the handle 43 by means of which the bobbin may be grasped by the operator. The lower portion of head 29 is in the form of a tapered flange 44 having a smooth polished edge 45 over which thread may 45 slide without being snagged or broken in passing to or from the bobbin. Lower head 30 is larger in diameter than body portion 28 in order to permit the thread to be wound on body portion 28 between the flange thus formed and the 50 flange 44 on upper head 29. If desired, a reinforcing portion 46 may be provided on the inside of lower head 30.

In the embodiment of the invention shown, two recesses 47 are provided in head 30 on opposite 55 sides of central bore 39 which recesses are adapted to engage suitable pins on the whorl on which the bobbin is mounted. Other means providing the necessary driving engagement can, of course, be employed in lieu thereof. The periphery of 60 head 30 is also provided with two slots 48 in which the thread may be engaged in starting the operation of winding the thread on the bobbin. One slot is adapted to engage the thread in case the rotation of the bobbin is to be clockwise, while 65 the other is adapted to engage the thread in case of counterclockwise rotation.

In the preferred construction of the bobbin, the parts which come into contact with the thread; i. e., body portion 28 and heads 29 and 70 30, are made of suitable non-metallic materials, while the tube 27 is of metal. The non-metallic parts can advantageously be made of hard rubber, Bakelite, or other suitable synthetic resin.

The heads 29 and 30 are preferably molded, while 75 the body portion 28 may be molded or, if de-

sired, cut from seamless tubing of such material. Because of the stresses induced in body portion 28 in the thread winding operation, it is desirable that it be of reinforced material; e. g., Bakelite-
5 impregnated fabric or the like.

Thus the parts which come into contact with the thread are made of materials which may be made with very hard, smooth surfaces. Since there is no grain structure, the edge of the upper flange, which is in frequent contact with the 10 thread, cannot split and snag the thread, a failing common in wooden bobbins. Such materials, moreover, do not absorb moisture to such an extent as to cause swelling or warping of the bobbin. Furthermore, the surfaces of the bobbin 15 may be cleaned easily when made of such materials.

In the present invention, such features are combined with the additional advantage that such a bobbin may, because of the type of construction employed, be light in weight and yet extremely strong. It is unusually rigid due to the fact that the non-metallic parts are held in compression, under which stress their strength is greatest, while the part which holds the device 25 together and hence is under tension is metal capable of withstanding high tensile stress. Yet the metal does not contact the thread at any point as a result of which feature it cannot damage the thread should it become corroded. In 30 case it is desired to replace one or more parts of such a bobbin, the bobbin may be readily disassembled and reassembled with such new parts. Such bobbins can be built at very low cost because of their extremely simple construction. 35

It is intended that the patent shall cover, by suitable expression in the appended claims, whatever features of patentable novelty reside in the invention.

What is claimed is:

1. A built-up bobbin comprising a hollow, seamless body portion of substantially circular cross section formed of non-metallic material; a unitary handle-shaped head of non-metallic material having a recess in its inner face in which recess one end of said body portion fits closely; a second unitary head of non-metallic material having a recess in its inner face in which recess the other end of said body portion fits closely; means associated with said second head providing driving engagement with means for rotating said bobbin; means associated with the recesses in the inner faces of said heads for preventing relative rotation between said body portion and said heads; and a seamless, unitary metal sleeve 55 passing axially through said body portion and heads, said metal sleeve being flanged into recesses formed in the external faces of said heads to hold said metal sleeve under tension and said heads and body portion under compression. 60

2. A built-up bobbin comprising a hollow, seamless cylindrical body portion; a unitary handle-shaped head having a recess in its outer face and, in its inner face, a recess in which one end of said body portion fits closely; a second unitary head having a recess in its inner face in which the other end of said body portion fits closely and, in its outer face, one or more recesses adapted to receive means for rotating said bobbin; a seamless, unitary metal sleeve expanded intermediate its ends passing axially through said body portion and heads, the ends of said sleeve being flanged over in said recesses in the outer faces of said heads to hold said metal sleeve under tension and said heads and body portion un- 75

der compression; and means adapted to prevent relative rotation between said heads and said body portion.

3. A built-up bobbin comprising a hollow, seam-less body portion of substantially circular cross section formed of non-metallic material; a unitary handle-shaped head of non-metallic material having a recess in its inner face in which recess one end of said body portion fits closely; 10 a second unitary head of non-metallic material having a recess in its outer face and a recess in its inner face in which latter recess the other

end of said body portion fits closely; means associated with said second head providing driving engagement with means for rotating said bobbin; and a seamless metal sleeve passing axially through said body portion and heads, one end of 5 said sleeve being flared over the outer surface of said handle-shaped head and the other end of said sleeve being flanged into the recess in the outer face of said second head in such manner as to hold said sleeve under tension and said 10 heads and body portion under compression.
